UNITED STATES PATENT OFFICE.

PAUL W. KEATING, OF OCHILTREE, TEXAS, ASSIGNOR OF ONE-HALF TO CHARLIE N. SMITH, OF OCHILTREE, TEXAS.

AIR-PUMP.

1,319,775.

Specification of Letters Patent.

Patented Oct. 28, 1919.

Application filed December 11, 1917. Serial No. 208,632.

To all whom it may concern:

Be it known that I, PAUL W. KEATING, a citizen of the United States, residing at Ochiltree, in the county of Ochiltree, State 5 of Texas, have invented certain new and useful Improvements in Air-Pumps; and I do hereby declare the following to be a full, clear, and exact description of the invention, such as will enable others skilled in the art 10 to which it appertains to make and use the same.

This invention relates to air pumps, and has particular reference to pumps which are usually utilized for inflating tires.

15 The object of the invention is to provide an air pump having a single cylinder, but operative to deliver equal quantities of air upon both the upward and downward strokes of the piston. More particularly, it 20 is the object of the invention to construct a double action pump of the type above mentioned which is simply constructed, and may be manufactured for wide use at a minimum cost. Thus, I provide a cylinder within 25 which the piston is operative, and upper and lower heads which include all of the valve mechanism and connections necessary to the operation of the pump, the heads being castings and the valve casings being simply constructed bushed elements fitted into the castings.

With the above objects in view, and such others relating to the details of construction as may hereinafter appear, my invention 35 will now be fully set forth and described, reference being had to the accompanying drawings.

In the drawings:—

Figure 1 is a side elevation,

10 Fig. 2 is a vertical section therethrough, Fig. 3 is a horizontal section through the upper cylinder head and

Fig. 4 is a horizontal section through the lower cylinder head.

15 Referring more particularly to the drawings, 1 represents the pump cylinder of suitable sheet metal tubing, which is exteriorly threaded at its ends to fit within an upper head casting 2 and a lower head casting 3, 20 the castings 2 and 3 having the flanges 4 and 5 respectively, raised therefrom to receive said threaded ends of the cylinder.

The head 2 is provided with a central bore within which a plug 6 is threaded, said plug 6 constitutes a guide for the piston rod

7 and carries a bushing 8 so that an air-tight joint may be maintained between the piston rod and the plug. A piston 9 which is operative in both directions is carried by the piston rod, and may be the usual double 60 leather piston which is used in most tire pumps.

The head 2 has formed at one side a valve recess 10 from which a right angularly turned port 11 extends to communicate with the interior of the cylinder 1. Threaded into the recess 10 is a valve plug 12 having a longitudinal bore 13. The bore 13 opens to the atmosphere by means of a port 14 passed through the head of the plug, and has its forward end shaped into a valve seat upon which the spherical valve body 15 is held by means of a spring 16, the opposite end of the latter bearing against the bottom of the recess 10. Thus, by screwing the plug 75 12 into or out of the recess 10, the tension of the spring 16 may be regulated. Upon its opposite side the head 2 is provided with a recess 17 into which a plug 18 is screwed, the plug 18 providing an abutment against 80 which one end of a spring 19 bears, the opposite end of the spring 19 exerting its pressure against a spherical valve body 20 to hold it upon a seat 21 cut into the bottom of the recess 17 around the end of a right 85 angular port 22. The inner end of the port 22 communicates with the interior of the cylinder 1, so that air from the latter may be forced past the valve body and into the recess 17, from which it issues through a 90 nipple 23 which extends downwardly from the overhanging portion of the head 2 which provides the valve casing into which the recess 17 is bored.

The head 3 also has bored into one side 95 a recess 24 into which a plug 25 is threaded, the plug 25 having the valve recess 26 and an inlet port 27 which leads into the recess 26. Leading from the recess 24 and terminating in the top of the head 3 so as to communicate with the interior of the cylinder 1 is a port 28 through which air which is received through the inlet 27 is passed onto the cylinder. The spherical valve body 29 is held upon a seat 30 at the forward end of the 105 valve recess 26, by means of the spring 31, the spring 31 being interposed between the valve body and the inner end of the recess 24. Opposite the valve casing 24, the head 3 is provided with a valve casing 32 110

within which a valve recess 33 is formed so as to communicate with the interior of the cylinder 1 through a port 34, a valve seat 35 between the port 34 and the valve recess 33 being normally closed by means of a spherical valve body 36. As is the case with the valve body 20, a spring 37 which is interposed between a plug 38 threaded into the end of the casing 32 and the valve body 36, holds the latter in resilient relation against the seat 35. Rising from the casing 32 is a nipple 39 which is connected to the nipple 23 above mentioned by means of a flexible hose 40, the hose 40 thus connecting the two valve recesses 17 and 33 so that the air which is alternately received in the upper and lower ends of the cylinder 1 is discharged into a common delivery tube 41.

The operation of the pump which has been described is obvious from the foregoing, but particular attention is directed to the fact that the pump is assembled from parts which are very simple in construction and which are easily accessible when it is necessary to repair or adjust the parts, particularly the valve mechanisms. By reason of the small number of inexpensive elements, coupled with the fact that the pump is a double action mechanism, it is possible to place them on the market at a comparatively low cost.

What I claim as my invention is:—

As an article of manufacture, an air pump comprising a tube having threaded ends, a

cap screwed onto each end of the tube, each of the caps having a pair of diametrically opposite and threaded radial recesses opening through its periphery and an air duct extending from the inner end of each recess to the inclosure of the tube, a valve in one recess of each pair disposed to close the duct leading therefrom, a plug adjustably screwed into and closing the outer end of each of the last named recesses, a spring tensioned between each plug and the corresponding valve in position to hold the latter normally and yieldably seated over its duct, a pipe connecting the last named recesses, one of the plugs having an air duct therethrough and being adapted for connection of a delivery pipe therewith, a valve within each of the remaining recesses, a plug having an inlet port therethrough and screwed into and inclosing the outer end of each of said remaining recesses, a spring disposed between each of the last named valves and the bottom of its recess, disposed to hold the valve yieldably to close the plug port and a double acting plunger within the tube having a rod extending exteriorly thereof.

In testimony whereof, I affix my signature in the presence of two witnesses.

PAUL W. KEATING.
